CLAIM

The ornamental design for a smoke removal vent for vehicle window, as shown and described.

DESCRIPTION

FIG. 1 is an environmental view of a smoke removal vent for vehicle window showing my new design installed in a vehicle;

FIG. 2 is a front elevational view thereof;

FIG. 3 is a rear elevational view thereof;

FIG. 4 is a top view thereof;

FIG. 5 is a bottom view thereof; and,

FIG. 6 is a right side elevational view with the left side being a mirror image thereof;

The broken line showing of the vehicle body, windscreens, door and side glass is for illustrative purposes only and forms no part of the claimed design.
